DESIGN FOR AN UPRIGHT DRILLING MACHINE

Lawrence L. Schauer, Wyoming, and John H.
McKewen, Cincinnati, Ohio

Application April 27, 1945, Serial No. 119,276

Term of patent 14 years

(Cl. D54—14)

To all whom it may concern:

Be it known that we, Lawrence L. Schauer and John H. McKewen, each a citizen of the United States, and residing respectively at Wyoming, in the county of Hamilton and State of Ohio; and at Cincinnati, in the county of Hamilton and State of Ohio, have jointly invented a new, original, and ornamental Design for an Upright Drilling Machine, of which the following is a specification, reference being had to the accompanying drawings, forming part thereof.

Fig. 1 is a side elevational view of an upright

drilling machine embodying our new design, with the base broken away for convenience of illustration; and

Fig. 2 is a perspective view showing the front and other side thereof. The back, not shown, is substantially plain.

We claim:

The ornamental design for an upright drilling machine, substantially as shown and described.
